United States Patent Office

Des. 198,355
Patented June 2, 1964

198,355

HEATER

Walter R. Kimberley, Centralia, Ill., assignor to Lear Siegler, Inc., Centralia, Ill., a corporation of Delaware

Filed Jan. 20, 1964, Ser. No. 78,246

Term of patent 14 years

(Cl. D81—19)

Fig. 1.

Fig. 2.

Fig. 3.

The back of the heater is plain.

I claim:

The ornamental design for a heater, substantially as shown and described.
